CLAIM

The ornamental design for a handbag, as shown and described.

DESCRIPTION

FIG. 1 is a front right perspective view of a handbag showing my new design;

FIG. 2 is a rear right perspective view thereof;

FIG. 3 is a front left perspective view with the chain retracted thereof;

FIG. 4 is a top view with the chain retracted thereof;

FIG. 5 is a bottom view with the chain retracted thereof;

FIG. 6 is a left side view with the chain retracted thereof;

FIG. 7 is a right side view with the chain retracted thereof;

FIG. 8 is a front view with the chain extended thereof;

FIG. 9 is a rear view with the chain retracted thereof; and,

FIG. 10 is a top perspective view with flap open with chain thereof.

The portions of the handbag shown in dashed lines represent stiches.
